UNITED STATES PATENT OFFICE.

EDWARD E. CLAUSSEN AND JOSEPH C. HAMMER, OF HARTFORD, CONNECTICUT.

FLOOR OR CEILING PLATE.

1,285,043.

Specification of Letters Patent. Patented Nov. 19, 1918.

Application filed February 18, 1917. Serial No. 143,434.

To all whom it may concern:

Be it known that we, EDWARD E. CLAUSSEN and JOSEPH C. HAMMER, citizens of the United States, residing at Hartford, in the 5 county of Hartford and State of Connecticut, have invented certain new and useful Improvements in Floor or Ceiling Plates, of which the following is a specification.

This invention relates to floor or ceiling 10 plates, the object of the invention being to provide an article of this character which has means of an effective nature for uniting the sections for relative swinging movement, for holding them closed when desired, and 15 for closing them. The invention can obviously be incorporated in plates of different character; that is to say a plate may have provision for the reception of one or a plurality of pipes or equivalent elements.

20 In the drawings accompanying and forming part of the present specification we have shown in detail certain forms of embodiment of the invention which will be set forth fully in the following description. We are 25 not limited in this particular, however; we may depart therefrom in several respects within the scope of the invention defined by the claims following said description.

Referring to said drawings:

30 Figure 1 is a rear view of a floor or ceiling plate involving the invention, the sections being separated and the spring dismounted.

Figs. 2 and 3 are transverse sections on the 35 lines 2—2 and 3—3 respectively of Fig. 1, looking in the direction of the arrows.

Fig. 4 is a view corresponding to Fig. 1 with the sections closed together and representing the spring in position.

Fig. 5 is a rear view and

40 Fig. 6 a side view of the spring appearing in Fig. 4.

Like characters refer to like parts throughout the several views.

The plate shown comprises the practically 45 duplicate halves or sections 2 and 3 which after the usual fashion may be struck up from sheet metal, although the material from which the sections or halves 2 and 3 are made is not a matter of consequence.

50 Sheet metal is as may be inferred, eminently desirable for the purpose. The sections 2 and 3 as shown are semi-circular, and they have along their outer ends rims or flanges 4 which extend backwardly, and the ends 55 of which are adapted to practically abut when the plate is closed. In the construction

shown the hinge members which unite the sections or halves 2 and 3 of the plate are rigid with the rear portions of the flanges 4, and as will be understood may vary decidedly. We have shown two of the several types of hinges which meet our conditions. In Fig. 1 the plate 2 is provided with a hinge member 5, while the plate 3 is equipped with a co-operating hinge member 6. The hinge member 5 is practically in the form of a hook constituting a continuation of the rear portion of the flange 4 of the section 2, being slotted as at 7 (Fig. 2) to receive the hinge member 6 which is also in 70 hook form, the bent base portion 8 of the hinge member 6 being intended to rock in the slot 7 as the sections 2 and 3 are swung toward or from each other. When the sections are closed as illustrated for instance 75 in Fig. 4, the free portion of the hinge member or element 6 will be adjacent the inner side of the marginal flange or bead 4 of the section 2 as illustrated in said view. As will be understood the hinge members 5 and 80 6 extend from the butt or hinge portions of the two sections 2 and 3, and when the said hinge members are in assembled relation the sections 2 and 3 can be freely opened and closed.

85 The sections or segments 2 and 3 in addition to the marginal flanges have flanges 9 along their apertures which mate as shown for example in Fig. 4 to form a circle, and these flanges at their forward ends or what 90 is the lower portions thereof in Fig. 1 are equipped with a catch to hold the sections of the plate closed. The flange 9 of the section 2 is equipped with a projection 10 of practically angular form which extends 95 from the front end of said flange, the outwardly extending branch of the angular projection 10 being slotted or notched as at 11 in its lower side. The front end of the flange 9 of the section 3 has a forwardly 100 extending projection or catch portion 12 which extends along the front end of said section 3 as shown in both Figs. 1 and 3. This catch portion 12 adjacent the flange 9 has a slot or notch 13. It will be assumed 105 that the parts 2 and 3 are connected together as illustrated in Fig. 4 for instance, and that they are in open position. To close them the following procedure will be adopted: They can be moved toward each 110 other and when they are nearly closed they will be moved relatively to each other in

a direction at right angles to their closing movement, so as to carry the projection 12 below the lower edge of the projection 10, the motion being continued until the slot 13 is opposite the slot 11 when the two sections 2 and 3 will be alined so as to project the slotted portion of the catch 12 into the slot 11 and thus maintain the closed relation.

In the construction shown in Fig. 4 the sections or halves 15 and 16 of the plate are hinged together as already described, and they have the outside or marginal flanges or beads 17 and 18 and the inner flanges or beads 19 and 20 counterparts of the flanges 4 and beads 9 already described in connection with Fig. 1. The halves or sections 15 and 16 are connected together by a hinge such as that denoted in a general way by 21, a counterpart of the hinge shown in Fig. 1 and already described in detail. The sections or halves are also fastened together by a catch such as that denoted in a general way by 22 which is precisely like that described in detail in connection with the showing of Fig. 1. In view of this condition the parts in question need not again be described. In Fig. 4 the sections 15 and 16 of the plate are closable toward each other by a spring such as that denoted in a general way by 23. This spring is shown in said Fig. 4 in place and is also shown separated from the plate or the sections thereof in Figs. 5 and 6. This spring is a suitable one for performing two offices, namely as a convenient means for constantly closing the sections or halves 15 and 16 toward each other and at the same time for engaging the pipe or equivalent which the plate or ring surrounds. While the spring in question serves suitably in this connection, one of an entirely different type might be substituted therefor, although the one shown and now to be described is advantageous. This spring comprises the portion 24 made up of the inwardly converging sides or legs 25 and the connecting portion 26 of compound curvature uniting the two sides, these parts as shown being integral. The compound curved part when the spring is in position crosses the joint at the rear of the plate as shown best in Fig. 4, and when the plate is opened in the manner already described, this connecting or compound curved portion and especially the bowed dipped intermediate part by acting upon the sides or legs acts to swing said legs toward each other, and the latter in turn by bearing against the sections or halves of the plate or ring close said sections toward each other. The flanges 19 and 20 have near their rear ends the outwardly extending lugs 27 which are engaged by the free portions of the sides 25. From these sides 25 project outwardly the bowed extensions 28 which are situated under the lugs 29 on the flanges

19 and 20 forward of the lugs 27 to thus aid in holding the spring 23 in position. The projections or arcuate extensions 28 are in the construction shown made comparatively long, so that they can present a convenient means for engaging a rod around which the plate made up of the sections 15 and 16 is fitted. The flanges 19 and 20 as shown have between their ends the lugs 30 against which the bowed extensions 28 are adapted to fit, said lugs 30 having at their rear ends the extensions 31 which overlie the bowed portions 28 between the ends thereof. As will be understood there may be cases where these bowed extensions 28 or their equivalents could be wholly dispensed with. We provide however, a spring which serves a double office as already noted, acting on the one hand when in position to close the sections of the plate toward each other, and at the same time to engage a pipe or rod which the plate or ring surrounds and the spring already described serves satisfactorily in this connection.

What we claim is:

1. A floor or ceiling plate comprising two approximately duplicate sections hinged to each other for relative swinging movement and of segmental form, the sections being openable to receive a pipe and being closable to fit around said pipe, and a bowed spring the branches of which extend into the opening presented by said sections and are also united with the sections the transverse portion of the spring being situated in proximity to the hinged joint between said sections.

2. A floor or ceiling plate comprising two approximately duplicate sections hinged to each other for relative swinging movement and of segmental form, the sections being openable to receive a pipe and being closable to fit around said pipe or equivalent, and a bowed spring the branches of which extend into the opening presented by said sections and are also united with the sections, the transverse portion of the spring being situated in proximity to the hinged joint between the sections, the latter having means at a point opposite the hinge for positively holding said sections in closed relation.

3. A floor or ceiling plate comprising two approximately duplicate sheet metal sections provided with peripheral flanges, the flanges having laterally-extending integral hinge members directly united with each other for connecting said sections for relative swinging movement, the sections being openable to receive a pipe or its equivalent and being closable to fit around said pipe or equivalent, the flanges having at a point remote from the hinge members catch means which coöperate to maintain the plate in closed form around said pipe, and a bowed spring the branches of which extend into the open-

ing presented by said sections and are also united with the sections, the transverse portion of the spring being situated in proximity to the joint between the sections.

- 5 4. A floor or ceiling plate comprising two approximately duplicate sections hinged together for relative swinging movement and of segmental form, the sections being openable to receive a pipe and being closable to fit around said object, and a bowed spring the branches of which extend into the opening presented by said sections, the latter having respectively lugs bent over said

branches, the transverse portion of the spring being situated in proximity to the 15 hinged joint between the sections, the latter having respectively additional lugs which overlie the branches of the spring between said other lugs and said hinge.

In testimony whereof we affix our signatures in the presence of two witnesses.

EDWARD E. CLAUSSEN.
JOSEPH C. HAMMER.
